J. H. SPANBURG

IGNITION APPARATUS

Filed April 22, 1922

INVENTOR.

John H. Spanburg

BY
Chappell & Earg
ATTORNEYS

UNITED STATES PATENT OFFICE.

JOHN H. SPANBURG, OF JACKSON, MICHIGAN, ASSIGNOR OF TWENTY-SIX ONE-HUNDREDTHREE TO GEORGE L. COTTON, OF JACKSON, MICHIGAN.

IGNITION APPARATUS.

Application filed April 22, 1922. Serial No. 556,122.

To all whom it may concern:

Be it known that I, JOHN H. SPANBURG, a citizen of the United States, residing at the city and county of Jackson, State of Michigan, have invented certain new and useful Improvements in Ignition Apparatus, of which the following is a specification.

This invention relates to improvements in ignition apparatus.

10 The main objects of the invention are:

First, to provide an improved ignition apparatus comprising timing and distributing mechanism which may be opened for inspection without affecting its operation and so that it may be inspected while operating.

15 Second, to provide an improved ignition apparatus in which the mechanism carrying the distributor contacts and to which the cables are connected constitutes a housing for the operating mechanism so that such parts may be fully exposed for cleaning or adjustment while in assembled relation.

20 Third, to provide in an ignition mechanism an improved distributor member to which the cables are connected so that short circuits are not likely to be caused by water, oil, dirt or the like.

25 Further objects, and objects relating to structural details, will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing, forming a part of this application, in which:

40 Fig. I is a side elevation of my improved ignition apparatus.

Fig. II is a plan view with the cap removed.

45 Fig. III is a vertical section through the annular distributor member and cap on a line corresponding to line 3-3 of Figs. I and II.

50 Fig. IV is a detail side elevation with the cap and distributor member removed exposing the operating parts for adjustment and cleaning.

55 In the drawing similar reference characters refer to similar parts throughout the several views.

Referring to the drawing, the body 1 is provided with an annular shoulder 2 on

which the annular distributor member 3 is seated. This annular distributor member 3 is formed of insulating material and constitutes a housing for the timer and distributor mechanism.

The cap 4 is removable from the distributor member 3. The spring hooks 5 are pivoted at 6 and adapted to engage the lugs or keepers 7 on the distributor member 3. 60 These hooks 5 have extention hooks 8 adapted to engage the cap, it being possible to disengage the hooks 8 without disengaging the hooks 5, so that the cap may be released and removed leaving the member 3 in its normal operative position.

The timing mechanism is mounted on the body member 1, the breaker cam 9 being mounted on the spindle 10 which also carries the distributor finger 11 having a brush 12 thereon. The contact point 13 is suitably mounted on the breaker plate 14, the coacting contact 15 being mounted on the lever 16 actuated by the cam. As the details of these parts form no part of this invention 70 they are not further described.

The distributor member 3 is provided with distributor cable contacts 17 mounted to coact with the brush 12. The distributor cable sockets 18 are suitably spaced about the distributor member 3 and are arranged to face downwardly so that the cables 19 are directed upwardly as they enter the sockets. The distributor member 3 also carries a terminal member 20 which is ordinarily connected to the coil. The socket 21 for this connection is also arranged to face downwardly.

75 A brush 22 is mounted on the distributor finger 11 to coact with the terminal member 20. A lug 23 on the cap 4 engages the terminal member 20 normally supporting it.

With this arrangement of parts the cap may be removed exposing the mechanism within for inspection so that the workmen may determine what manipulations are required. The distributor member 3 may then be removed and the parts are fully exposed for cleaning or adjustment or renewal, as 100 may be desired.

105 I have illustrated and described my improvements in the form in which I have found very practical. I have not attempted to illustrate or describe certain modifications or adaptations which I contemplate as I believe the disclosure made will enable those skilled in the art to which my inven-

tion relates to embody or adapt the same as may be desired.

Having thus described my invention, what I claim as new and desire to secure by Letters Patent, is:

1. In an ignition apparatus, the combination of a body member, a timer mechanism provided with a distributor brush mounted on said body member, an annular distributor member removably mounted on said body member and constituting a housing for said mechanism and having contacts mounted on the inner side thereof to contact with said distributor brush and a circuit terminal projecting centrally above said timer mechanism, said timer mechanism having a brush coacting with said terminal, the parts of said timer mechanism mounted on said body being exposed for adjustment and cleaning when said distributor member is removed, a removable cap for said distributor member provided with an internal central lug engaging said terminal when the cap is in position, and retaining hooks for said distributor member mounted on said body and provided with auxiliary hooks engaging said cap, said auxiliary hooks being adapted to be released without releasing said distributor member so that the cap may be removed without affecting the operation of the mechanism.
2. In an ignition apparatus, the combination of a body member, a timer mechanism provided with a distributor brush mounted on said body member, an annular distributor member removably mounted on said body member and constituting a housing for said mechanism and having contacts mounted on the inner side thereof to contact with said distributor brush, the parts of said timer mechanism mounted on said body being exposed for adjustment and cleaning when said distributor member is removed, a removable cap for said distributor member, and retaining hooks for said distributor member mounted on said body and provided with auxiliary hooks engaging said cap, said auxiliary hooks being adapted to be released without releasing said distributor member so that the cap may be removed without affecting the operation of the mechanism.
3. In an ignition apparatus, the combination of a body member, a timer mechanism provided with a distributor brush mounted on said body member, an annular distributor member removably mounted on said body member and constituting a housing for said mechanism and having downwardly facing sockets grouped about the same, and contacts mounted on the inner side thereof to contact with said distributor brush, the parts of said timer mechanism mounted on said body being exposed for adjustment and cleaning when said distributor member is removed, a removable cap for said distributor member, and retaining means for said distributor member and cap permitting the releasing of the cap independently of the distributor member.
4. In an ignition apparatus, the combination of a body member, a timer mechanism provided with a distributor brush mounted on said body member, annular distributor member removably mounted on said body member and constituting a housing for said mechanism and having contacts mounted thereon to contact with said distributor brush and a circuit terminal projecting centrally above said timer mechanism, said timer mechanism having a brush coacting with said terminal, the parts of said timer mechanism mounted on said body being exposed for adjustment and cleaning when said distributor member is removed, a removable cap for said distributor member provided with an internal central lug engaging said terminal when the cap is in position, and retaining means for said distributor member and cap permitting the releasing of the cap independently of the distributor member.
5. In an ignition apparatus, the combination of a body member, a timer mechanism provided with a distributor brush mounted on said body member, an annular distributor member removably mounted on said body member and constituting a housing for said mechanism and having contacts mounted thereon to contact with said distributor brush, the parts of said timer mechanism mounted on said body being exposed for adjustment and cleaning when said distributor member is removed, a removable cap for said distributor member, and retaining means for said distributor member and cap permitting the releasing of the cap independently of the distributor member.
6. In an ignition apparatus, the combination of a body member, a timer mechanism provided with a distributor brush mounted on said body member, an annular distributor member removably mounted on said body member and constituting a housing for said mechanism and having downwardly facing cable sockets grouped about the same, and contacts mounted thereon to contact with said distributor brush, the parts of said timer mechanism mounted on said body being exposed for adjustment and cleaning when said distributor member is removed, a removable cap for said distributor member, and retaining means for said distributor member and cap permitting the releasing of the cap independently of the distributor member.
7. In an ignition apparatus, the combination of a body member, a timer mechanism and distributor brush mounted on said body member, an annular distributor member

provided with cable contacts removably mounted on said body member and constituting a housing for the mechanism mounted on said body member, such mechanism being exposed on the removal of said distributor member, a removable cap for said distributor member, and retaining

means for said distributor member and cap permitting the release of the cap independently of said distributor member. ¹⁰

In witness whereof, I have hereunto set my hand and seal.

JOHN H. SPANBURG. [L. s.]
